THE NORRIS PETERS CO., PHOTO-LITHO., WASHINGTON, D. C.

UNITED STATES PATENT OFFICE.

JAMES BURNS, OF CINCINNATI, OHIO.

HEARSE.

SPECIFICATION forming part of Letters Patent No. 595,116, dated December 7, 1897.

Application filed May 28, 1897. Serial No. 638,530. (No model.)

To all whom it may concern:

Be it known that I, JAMES BURNS, of Cincinnati, in the county of Hamilton and State of Ohio, have invented a new and Improved 5 Hearse, of which the following is a full, clear, and exact description.

This invention is a hearse having a table to carry a casket, and that slides forward and backward and admits of very readily placing 10 the casket in the hearse or removing the casket from the hearse.

This specification is the disclosure of two forms of my invention, while the claims define the actual scope of the conception.

15 Reference is to be had to the accompanying drawings, forming a part of this specification, in which similar characters of reference indicate corresponding parts in all the figures.

Figure 1 is a side elevation of the invention, with parts in section. Fig. 2 is a horizontal section of the invention. Fig. 3 is a cross-section on the line 3 3 of Fig. 2 and enlarged over the scale thereof. Fig. 4 is a longitudinal section of the invention on the line 25 4 4 of Fig. 5. Fig. 5 is a horizontal section of the invention on the line 5 5 of Fig. 4. Fig. 6 is a cross-section of the invention on the line 6 6 of Fig. 5 and reduced over the scale thereof, and Fig. 7 is a partly-sectional 30 view showing a modified construction of the device for holding the table for the casket.

The form of my invention shown in Figs. 1, 2, and 3 is characterized by a full table 10, having secured to its under face brackets 11, 35 projecting laterally beyond the side edges of the table 10 and each carrying two rollers, (designated as 12 and 13.) The rollers 12 have horizontal axes and run in grooves 14, formed in the moldings 15, that are produced at the 40 sides of the hearse and within the outer walls thereof. The rollers 13 bear against the inner faces of the moldings 15. The rollers 12 support the table 10, while the rollers 13 prevent lateral deviation thereof. The table 10 45 is held at all times in horizontal line with the upper faces of the moldings 15.

The table 10 has a series of plates 16 let into the upper surface thereof and carrying pins 17. The plates 16 are provided with a 50 series of openings in which the pins may be removably seated, so that they may be adjusted to suit the size and position of the

casket. The table 10 is also provided with carrying-rollers 18, projecting slightly above the upper surface thereof and designed to 55 have the casket rested thereon. The casket is shown by dotted lines in Fig. 1. The rear edge of the table 10 has a roller 19 let into the same and designed to have the casket engaged with the roller as the casket is placed 60 in or removed from the hearse. This construction permits the table 10 to be moved in and out of the hearse and allows the pall-bearers all freedom of movement in depositing and removing the casket. The mounting 65 of the table in the runways 14 and the other devices connected with these parts cause the table to be very strong and rigid and well adapted for the service that it is to perform.

In the form of my invention shown in Figs. 70 4, 5, and 6 the table 10^a moves up and down, as well as forward and backward, the special purpose of which arrangement is to lower the table and thus decrease the height to which it is necessary to raise the casket. The table 75 10^a has plates 16^a, which, like the plates 16, are designed to receive pins 17. The table 10^a has rollers 18^a, that carry the casket, and has a roller 19^a at the rear edge, on which the casket rolls in its passage to and from the table 10^a.

The under face of the table 10^a is provided adjacent to each edge with four brackets 20, 21, 22, and 23. Each bracket 20 carries a roller 24 with a horizontal axis and a roller 25 85 with a vertical axis, and each bracket 21 carries a roller 26 with a horizontal axis and a roller 27 with a vertical axis. Each bracket 22 carries a roller 28 with a vertical axis and two rollers 29 with horizontal axes, and each 90 bracket 23 carries a roller 30 with a horizontal axis and a roller 31 with a vertical axis. The rollers 25, 27, 28, and 31 at each side of the table 10^a are in longitudinal alinement and bear against the inner faces of the moldings 15^a of the hearse. The rollers 24 and 30 95 at each side of the table 10^a are respectively in longitudinal alinement with each other, while the rollers 26 and 29 at each side of the table are out of alinement with each other. 100

The inner face of each molding 15^a has four track-grooves, (designated as 32, 33, 34, and 35.) The track-grooves 35 are at the rear ends of the moldings 15^a and near the upper faces

thereof, these grooves 35 being comparatively short and receiving the rollers 30 as the table 10^a is raised to its uppermost and forwardmost position. When the table is drawn out, 5 the rollers 30 are without support, as shown in Figs. 4 and 5. The rollers 29 run in the slots 34, which slots are next in forward contiguity to the slots 35, while the slots 33 carry the rollers 26 and are next in forward 10 contiguity to the slots 34. The slots 32 carry the rollers 24 and are forwardmost of all the slots. The slots 32, 33, and 34 are of increased depth, so that they may properly accommodate the brackets 21 and 22. The upper end of each 15 slot has a horizontal portion in which the rollers for the slots are designed to rest when the table 10^a is in its uppermost and forwardmost position. The brackets 22 have two rollers with horizontal axes, because a strong 20 support is necessary at the points of the brackets 22, owing to the fact that they form the rearwardmost support for the table 10^a when the table is extended to the position shown in Figs. 4 and 5. This construction permits the 25 table to be not only drawn out but to be lowered, so that the pall-bearers may with great convenience place the casket upon the table. The rollers running in the several slots form a very easy bearing for the table and permit 30 the table to be operated by the expenditure of but a slight amount of energy.

The tables 10 and 10^a may be moved in and out of the hearse by any desired devices, and this movement may be by manual force. If 35 desired, a connection (indicated by the dotted lines 36 in Fig. 5) may be employed, so that manual force may be exerted from the driver's seat for deeper inclines.

In Fig. 7 is shown a device by which the 40 table for the casket may be held steadily in place when the table is extended to receive the casket and also when the table is pushed in and the doors of the hearse are closed. The device shown in Fig. 7 consists in a staple 50, having its arms, one of which is longer 45 than the other, removably seated in openings formed in the bottom or flooring 51 of the hearse and in the moldings 15. (See Fig. 3.) This staple is capable of embracing any of 50 the brackets 20, 21, 22, and 23 (shown in Fig. 5) and the brackets 11, (shown in Fig. 2,) by which the brackets may be held securely engaged and consequently steadily hold the table for the casket. By adjusting the brackets 55 the table may be held in any desired position. The table can also be taken out entirely for cleaning purposes.

Various changes in the form, proportions, and minor details of my invention may be 60 sorted to without departing from the spirit

and scope thereof. Hence I do not consider myself limited to the precise construction herein shown, but believe that I am entitled to all such variations as come within the terms of my claims.

Having thus described my invention, I claim as new and desire to secure by Letters Patent—

1. The combination with parallel moldings having slots therein, of a full table movable 70 between the moldings, brackets carried by the table, and rollers held in the brackets and running in the slots.

2. The combination with parallel moldings having guideways, of a full table movable 75 between the moldings, brackets carried by the table, and rollers carried by the brackets and respectively running in the guideways.

3. A hearse having rigid moldings run parallel with each other at the sides of the hearse, 80 each molding having a groove therein, a full table located between the moldings, brackets secured to the table, and two rollers carried by each bracket, one roller of each bracket running in a respective slot, and the second 85 roller of each bracket bearing against the inner faces of the moldings.

4. The combination with moldings laid parallel with each other and having grooves therein, of a full table movable between the 90 moldings, brackets carried by the table, and two rollers carried by each bracket, one roller of each bracket having a horizontal axis, and the second roller of each bracket having a vertical axis, the rollers with horizontal axes 95 running in the grooves and the rollers with vertical axes bearing against the inner faces of the moldings.

5. A hearse having two moldings respectively at the sides thereof, each molding having a plurality of inclined grooves formed therein, a full table located between the moldings, and rollers carried by the table and respectively running in the grooves whereby the table may slide with a combined up-and-down and forward-and-rearward movement.

6. A hearse having side members running longitudinally with the hearse and separated from each other, and a full table mounted between and supported by the side members, 110 the table running in guideways having a downward and rearward inclination whereby the table moves forward and rearward in and out of the hearse and downward as it approaches its outer position.

JAMES BURNS.
